UNITED STATES PATENT OFFICE.

JOHN P. SUNDIN, OF SALEM, OREGON.

CLOTHES-DRAINER.

1,238,954.

Specification of Letters Patent. Patented Sept. 4, 1917.

Application filed January 4, 1917. Serial No. 140,582.

To all whom it may concern:

Be it known that I, JOHN P. SUNDIN, a citizen of the United States, residing at Salem, in the county of Marion and State 5 of Oregon, have invented a new and useful Clothes-Drainer, of which the following is a specification.

The present invention appertains to clothes drainers for wash boilers, and is 10 particularly an improvement over the clothes drainer disclosed in my Patent No. 1,190,606 granted July 11, 1916.

It is the object of the invention to provide novel and improved means applicable 15 to various wash boilers, and operable in a convenient and simple manner for raising the clothes holder or elevator out of the boiler, whereby to drain the clothes.

It is also the object of the invention to 20 provide a device of the nature indicated which is simple in construction, which can be manufactured cheaply, which is easy and practical to handle, which can be readily removed from the boiler when not needed, 25 and which is otherwise of advantage.

With the foregoing and other objects in 30 view which will appear as the description proceeds, the invention resides in the combination and arrangement of parts and in 35 the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a longitudinal section of a 40 wash boiler and clothes holder or elevator therein illustrating the invention applied thereto, the parts being shown in full lines with the holder lowered into the boiler, and in dotted lines with the holder elevated, 45 portions being broken away.

Fig. 2 is an end view of the boiler illustrating one part of the device in position with the holder lowered.

Fig. 3 is a fragmental plan view of one 50 end of the boiler and holder illustrating the lower portion of the respective standard in section.

Fig. 4 is a fragmental perspective view of one lever.

Fig. 5 is a section on the line 5—5 of Fig. 6.

Fig. 6 is an elevation of the parts shown in Fig. 5.

In the drawing, there is illustrated an ordinary wash boiler 1 in which a clothes holder or elevator 2 is disposed for vertical movement, said holder being apertured to permit the water to drain therefrom when the holder is elevated out of the boiler.

The present attachment or device is composed of two parts adapted to be carried by the opposite ends of the boiler 1, and to conveniently attach the device to the boiler. Plates 3 are riveted or otherwise secured to the inner surfaces of the ends of the 70 boiler adjacent to its upper edge, and are provided with instruck portions 4 providing vertical sockets for receiving a pair of standards 5, which, as illustrated, are formed from wire or equivalent stock. The 75 wire of each standard has lower downwardly projecting portions 6 embraced by a sheet metal sleeve 7 which can be readily slipped downwardly into the respective socket 4, and the wire is provided above 80 and spaced from the portions 6 with vertical portions 8 embraced by a sleeve 9. Between the sleeves 7 and 9, the wire is provided with coils 10, and a loop 11 extends to one side from the standard adjacent to 85 said coils, and is resilient, being provided at its free end or bend with an upwardly curved hook 12 providing a catch. Said loop has its ends bent similar to the coils 10 and extended upwardly within the sleeve 90 9. There are coils 10 between the loop 11 and the vertical portions 8, and the loop 11 and coils 10 can be formed in any suitable manner between the sleeves 7 and 9. Above the sleeve 9, the wire of the standard is 95 formed into an upstanding fork 13 and the ends of the arms of the fork are formed with pairs of coils 14 and arches 15 between the coils of each pair. A transverse rod 16 is engaged through the coils 14 100 which form bearings for said rod, and pulley wheels 17 are rotatable upon said rod 16 between the coils 14 of the two pairs within the arches or yokes 15.

Cords or other flexible elements 18 are 105 passed over the pulley wheels 17 and their inner ends are attached to the holder 2 in any suitable manner, while the outer ends of said cords are connected to levers 19 which are manipulated for raising and lowering the 110 clothes holder. Each lever 19, as illustrated, is formed from wire, which has adjacent

portions 20 embraced by a sleeve 21, the wire having eyes or loops 22 at one end of the sleeve 21 pivotally engaging a fulcrum pin 23 extending through the coils 10 of the 5 respective standard, said eyes 22 being located between the two sets of coils 10 of the standard to hold the lever in place. The wire is formed with a fork 24 projecting from the other end of the sleeve 21, and the 10 ends of the arms of the fork are connected by a cross piece 25 upon which a coiled wire handle 26 is mounted. The outer ends of the cords 18 of each pair are connected to the 15 ends of the arms of the respective fork 24. The levers 19 are fulcrumed to the standards whereby they can be swung upwardly and inwardly against the standards and outwardly and downwardly away from the standards.

20 In operation, when the levers 19 are swung upwardly and inwardly, the cords 18 are slackened, so that the holder 2 lowers into the boiler 1, and when the levers 19 are swung outwardly and downwardly, the cords 25 18 are pulled to raise the holder 2 out of the boiler for draining the clothes in order that they can be removed from the holder 2 conveniently. The catches 12 snap into engagement with the crotch portions of the forks 30 24 and respective ends of the sleeves 21 when the levers 19 are swing downwardly, thereby holding said levers in lower position, to maintain the holder 2 in elevated position, but the levers 19 can be moved out of 35 engagement with the catches to enable the holder 2 to be lowered.

Having thus described the invention, what is claimed as new is:

1. The combination with a wash boiler 40 and a clothes holder movable therein, of a standard constructed of wire having a lower portion applicable to the wash boiler, an upper fork, coils between said fork and

lower portion, and a loop extending from said standard and bent to form a hook-catch, a pair of flexible elements connected to the holder, the upper ends of the arms of said fork having means for guiding said elements, a fulcrum pin extending through said coils, and a lever fulcrumed upon said pin 45 between the coils, said elements being connected to the free end of the lever, and the lever being engageable with said catch when moved downwardly to be held thereby.

2. The combination with a wash boiler 55 and a clothes holder movable therein, of a standard constructed of wire having a lower portion applicable to the wash boiler, an upper fork, coils between said fork and lower portion, a loop extending from said standard and bent to form a hook-catch, the upper ends of the arms of said fork having pairs of spaced coils and yokes connecting said coils, a transverse pin extending through the last mentioned coils, pulley 60 wheels upon said pin within said yokes, a pair of flexible elements extending over said pulley wheels and connected to the holder, a fulcrum pin extending through the first mentioned coils, a lever fulcrumed at one 65 end upon the fulcrum pin between the first mentioned coils, said lever having a fork, the crotch portion of which is engageable with said catch when the lever is swung downwardly, the flexible elements being connected to the ends of the forked arms of the lever, and a handle between and connected to the forked arms of the lever.

In testimony that I claim the foregoing as my own, I have hereto affixed my signature 75 in the presence of two witnesses.

JOHN P. SUNDIN.
